DUAL FIRING RATE OIL BURNER WITH
NOZZLE PURGING MEANS

Joseph A. Logan, Hadley, Mass., assignor to Gilbert & Barker Manufacturing Company, West Springfield, Mass., a corporation of Massachusetts

Application December 30, 1946, Serial No. 719,164

2 Claims. (Cl. 158—36.3)

1

This invention relates to improvements in oil burners of the intermittently-operated type, such as are adapted for house heating service, wherein two oil-atomizing nozzles are employed and are adapted for operation alternately.

The invention has for its object the provision in a burner of the class described of valve means for selectively connecting the nozzles to the pressure side of the fuel supply pump and concurrently purging the unselected nozzle by connecting it to the suction side of the pump.

The invention will be disclosed with reference to the accompanying drawings in which:

The figure is a diagrammatical view of an oil burner embodying the invention.

Referring to Fig. 1 the burner includes two nozzles 1 and 2, both of the oil pressure atomizing type. These nozzles 1 and 2 may have different capacities. As an illustration, the respective capacities may be 1 and 2 gallons per hour. These nozzles are mounted side by side near the outlet end 3 of the air tube 4 of the burner. Oil is supplied to the nozzles by means of a pump 5, which draws in oil from a suitable supply tank (not shown) through a suction pipe 6. The pumped oil is forced outwardly through the casing of a by-pass valve 7 into the casing of a cut-off valve 8. The cut-off valve opens when the pumped oil attains a predetermined minimum pressure, say 85 pounds per square inch, and allows oil to flow into an outlet pipe 9 and thence to the nozzles as will be later described. The by-pass valve 7 opens when the pumped oil attains a predetermined maximum pressure, say 100 pounds per square inch, and allows some of the pumped oil to flow through a by-pass 10 back to the suction side of the pump, as to pipe 6. The valve 7 serves to regulate the pressure of the oil supplied to the nozzles and to maintain such pressure constant at the desired predetermined value.

The nozzles 1 and 2 may be used one at a time. They are adapted to be connected to the pressure side of the pump by a valve contained in a suitable casing 11. This valve comprises two interconnected discs 12 and 13 slidable in a cylinder 14 in casing 11. A spring 15 yieldingly holds this valve in the illustrated and low firing rate position. A solenoid 16 is adapted, when energized, to move its core 17, which is fixed to the stem of the aforesaid valve, and move the valve into its other and high firing rate position. With the valve in its low firing rate position, oil from outlet conduit 9 enters through a passage 18 into cylinder 14 at a location between discs 12 and 13 and passes into a passage 19, leading to a valve

2

chamber 20 in casing 11 and thence through a conduit 21 to the low rate nozzle 1. There is a float valve 22 in chamber 20 which will open to permit flow toward the nozzle. The nozzle 2 is connected by a conduit 23 with a valve chamber 24 in casing 11 and thence by a passage 25 in said casing to cylinder 14, opening into the latter at a location above the disc 13, when the latter is in its low firing rate position, and therefore flow of oil into passage 25 is prevented. When the valve 12, 13 is moved to its high firing rate position, the disc 13 will lie above passage 25 and disc 12 will lie above passage 19 and below passage 18. Thus, the supply of oil to the low rate nozzle 1 will be cut off and the passages 18 and 25 will be connected to supply oil to the high rate nozzle 2. There is a float valve 26 in chamber 24, which will open to permit oil to flow to nozzle 2. It will thus be seen that by actuation of valve 12, 13, the pressure side of pump 5 can be connected either to the low rate nozzle 1 or to the high rate nozzle 2.

Air for combustion is supplied by a fan 27, located within a casing 28 which connects with tube 4. The inlet to the fan is shown at 29. Such inlet is controlled by a shutter 30, located within a hollow housing 31, having air inlet openings 32. The shutter is threaded on a screw 33, which is mounted for rotatable as well as axial sliding movement. By turning the screw, the position of the shutter may be adjusted with precision for the low firing rate. The shutter is moved to its high rate position by bodily moving screw 33 in an axially outward direction against the force of a spring 34, which tends to hold it in the illustrated position. The screw is bodily moved by the solenoid 16, when energized, the upper end of the plunger 17 of the solenoid being pivotally connected to one end of a lever 35, 40 pivoted at 36 and having its other end forked to straddle screw 33. This forked end is adapted to engage a nut 37 on the screw and move the latter axially outward. The extent of axially outward movement will depend on the position of nut 37 on screw 33 and the high firing rate position of the shutter 30 may be adjusted with precision by manual adjustment of nut 37.

An electric motor 38, which is secured to fan casing 28, drives pump 5 and fan 27 by means of a suitable transmission, represented merely conventionally in Fig. 1 by the shaft 39. The motor is controlled in any suitable way, usually by means of a room thermostat switch 40 in the conventional manner. For example, the switch 40 is connected in series with a relay coil 41 in a circuit

which is supplied from the secondary 42 of a transformer and which includes wires 43, 44 and 45. The primary 46 of this transformer is connected by wires 47 and 48 to line wires 49 and 50, respectively, which lead from a suitable source of electricity. The relay coil 41, when energized by the closing of thermostat switch 40, actuates a switch 51 to close a circuit to motor 38; which circuit may be traced as follows—from line wire 50 by wire 52, switch 51, wire 53, motor 38 and wire 54 to line wire 49.

Ignition of the combustible mixture may be effected by sparks produced across a pair of electrodes 55, suitably mounted in tube 4 in proper igniting relation with the spray from either nozzle. These electrodes are connected by a pair of wires 56 to the secondary 57 of a suitable ignition transformer. The primary 58 of this transformer is connected by wires 59 and 60 to the motor wires 53 and 54, respectively. The ignition means is thus rendered active simultaneously with the motor 38.

The valve 12, 13, which varies the firing rate, may be actuated manually or automatically in various ways as desired. For example, it may be actuated automatically in response to outdoor temperature to provide for the high firing rate in severely cold weather and for the low firing rate in milder weather. For this purpose, a thermostat switch 61, located to respond to outdoor temperature, is arranged to close a circuit to the valve shifting solenoid 16, whenever the outdoor temperature falls sufficiently low, say for example 20° F. This circuit may be traced as follows—from line wire 50, by wire 52, switch 51, wire 53 as far as a wire 62, wire 62, thermostat switch 61, wire 63, solenoid 16 and wire 64 to line wire 49. This circuit is dominated by relay switch 51 and thus by room thermostat switch 40. That is, the outdoor thermostat switch 61 may close if the temperature falls low enough and thus predetermine a high firing rate but the shift to a high firing rate will not occur until the room thermostat switch 40 closes and starts the burner. Then, and then only, will solenoid 16 be energized to shift valve 12, 13 to position to produce a high firing rate.

The firing rate selector valve 12, 13 may also be operated manually if desired. Many of the benefits of the dual firing rate burner can be had even if the selector valve has to be shifted manually. For convenience, the manual shifting may be effected by remote control. For example, a push button switch 65, connected by wires 66 and 67 to the wires 62 and 63, serves in the same manner as the thermostat switch 61 to connect the solenoid 16 in circuit so as to be energized when the room thermostat switch 40 closes on a demand for heat from the burner. This push button switch may be located at any convenient point in one of the living rooms of the house and it enables the selector valve to be shifted without going into the cellar to reach the burner. It is, however, obvious that the valve 12, 13 might be operated by a hand lever (not shown) located at the burner.

In the practical operation of a burner of the type described the weather conditions are often such that the burner may operate at the low firing rate for many consecutive days. And it is also true, that the burner can operate at the high firing rate for long intervals and even for several consecutive days. This is one reason why automatic shifting of the firing rate selector valve is not so essential and manual shifting of this valve is practical. There is, however, a decided

disadvantage in allowing one nozzle to remain idle for long intervals while the other nozzle is operating. The idle nozzle and its feed conduit remain filled with oil which is not in motion.

5 Heat from the combustion produced by the other nozzle is reflected back and heats up the oil in the idle nozzle and in the immediately adjacent portion of the feed conduit. Some of the heat, reflected back as described to the nozzle and its 10 feed conduit, will be dissipated to the air stream flowing in tube 4, but unless the heat is dissipated as fast as it is received, which is not likely, the temperature of the motionless body of oil in the nozzle and feed conduit will increase, and, if the 15 temperature gets high enough, the oil will crack and carbon will be deposited in the nozzle or its feed conduit. Carbon deposits in the nozzle or in the feed conduit will eventually cause stoppage of the nozzle or its feed conduit and render the 20 nozzle inoperative.

This invention overcomes the difficulty described by providing for the removal of oil from either nozzle, when it is not in use, and for the withdrawal of oil from at least that portion of the 25 feed conduit which is exposed to high heat from the burner's flame. One way of accomplishing this result is to connect each nozzle to the suction side of the pump 5 when the other nozzle is connected to the pressure side. This may be effected by the selector valve 12, 13, operating in connection with suction ports 68 and 69 in cylinder 14. These ports are interconnected by a passage 70 in casing 11 and such passage is connected by a conduit 71 to the by-pass pipe 10 which 30 in turn connects with the suction conduit 6 of pump 5. A check valve 71 is interposed in conduit 71 to prevent back flow of oil from the supply tank under gravity head. When this selector valve is in its low firing rate position, the lower 35 suction port 69 is blocked off by valve disc 12. The upper suction port 68 is connected to conduit 25, since both this port and conduit lie above the valve disc 13. Hence, suction is applied to the nozzle 2, its conduit 23, valve chamber 24 and conduit 25. The float valve 26 will be open to 40 allow withdrawal of the oil by the suction of pump 5. Such withdrawal continues until the oil level in chamber 24 falls low enough to allow valve 26 to close. The nozzle 2 and its feed conduit 23 will then have been completely emptied. The valve 26 closes to prevent entry 45 of air into the pump. When the burner is later started up at the high firing rate, the air in chamber 24 and conduit 23 will be readily driven out through the nozzle 2. When the selector valve is shifted to its high firing rate position, the valve disc 13 blocks off the upper suction port 68 and valve disc 12 rises above the lower suction port 69 and above the entrance end of passage 50 19 and thus connects the latter to the suction side of pump 5. The float valve 22 being then open, oil is withdrawn from nozzle 1 and its feed conduit 21 until the level in chamber 20 falls low enough to allow valve 22 to close. The low rate 55 nozzle 1 and its feed conduit will then have been completely emptied. The arrangement thus insures the emptying of either nozzle and its feed conduit when either one is not connected to receive oil from the pump.

70 In the operation of the invention the burner is started up automatically by room thermostat 40 when there is a demand for heat. Oil will be supplied by pump 5 to nozzle 1 or 2 depending on whether either the outdoor thermostat switch 61 or the switch 65 is open or closed. If both

these switches are open, the burner will be operated at the low rate while if either switch is closed, the burner will operate at the high rate. Air will be supplied by the fan at a high or low rate according to whether the selector valve is set for high or low rate firing. The air supplied through tube 4 will mix with the atomized oil emitted from nozzle 1 or 2, as the case may be, and the combustible mixture will be ignited by a spark produced between the electrodes 55. When either nozzle is connected to the pressure side of the pump 5, the other nozzle is connected to the suction side of this same pump and the idle nozzle and its oil feed conduit are emptied of oil back as far as the float valve chamber 20 or 24 as the case may be. The float valves 22 and 26 serve to close their oil feed conduits when oil has been withdrawn from their respective chambers 20 or 24 down to a predetermined level. These float valves serve to prevent air, which enters the idle nozzle and passes into its oil feed conduit, from reaching the valves 7 or 8 and pump 5. Any air entering the nozzle and its oil feed conduit up to the point described is readily driven out when that conduit is subsequently connected to the pressure side of the pump.

The invention has been described in connection with a pressure atomizing burner of the dual firing type as an illustrative example of one important use. Another use for the invention is in connection with a burner of the same type where the two nozzles may be of the same size and one is provided as a standby nozzle for use when the other nozzle becomes disabled. Obviously, it is important for the same reason to withdraw oil from the standby nozzle and the immediately adjacent part of its oil feed conduit when such nozzle is idle, and the same means, herein disclosed, may be used for the purpose. The invention is generally applicable wherever the pressure atomizing burner has more than one nozzle and all nozzles are not always operated at the same time. If one nozzle lies idle, while another is operating, the invention is needed in order to withdraw oil from the idle nozzle and avoid the possibility of trouble due to carbonization and this, of course, is true regardless of whether the nozzles have the same or different capacities.

Having disclosed the invention, I claim:

1. In an oil burner, an oil supply pump, two oil conduits, an atomizing nozzle on one end of each conduit, and a valve for connecting one or the other of said conduits at their other ends to the pressure side of said pump to supply oil under pressure to a selected one of said nozzles, said valve when moved to connect the conduit of one nozzle to the pressure side of said pump being operable to connect the conduit of the other nozzle to the suction side of said pump, whereby to purge the unselected nozzle.

2. In an oil burner, an oil supply pump, two oil conduits, an atomizing nozzle on one end of each conduit, a valve for connecting one or the other of said conduits at their other ends to the pressure side of said pump to supply oil under pressure to a selected one of said nozzles, said valve when moved to connect the conduit of one nozzle to the pressure side of said pump being operable to connect the conduit of the other nozzle to the suction side of said pump, whereby suction may be applied to the unselected conduit to purge the unselected nozzle, and a float valve located in each conduit between its nozzle and said valve and operable to close such conduit after oil has been drawn out of it up to the float valve and prevent air from entering the pump.
